CLAIM

The ornamental design for an earphone, as shown and described.

DESCRIPTION

FIG. 1 is a front, bottom perspective view of an earphone showing my new design.

FIG. 2 is a rear, top perspective view of the earphone.

FIG. 3 is a front view of the earphone.

FIG. 4 is a rear view of the earphone.

FIG. 5 is a left view of the earphone.

FIG. 6 is a right view of the earphone.

FIG. 7 is a top view of the earphone; and,

FIG. 8 is a bottom view of the earphone.

Any shading and cross-hatching are not features of the design but are utilized to illustrate the surface contours of the earphone design in the drawings.

The broken lines depict portions of the earphone that form no part of the claimed design.
